COLLATING MACHINE

Lewis C. Pearce, Berea, Ohio, assignor to American Greetings Corporation, Cleveland, Ohio, a corporation of Ohio

Filed Sept. 20, 1955, Ser. No. 535,492
19 Claims. (Cl. 270—58)

This invention relates to improvements in a sheet-handling machine using sheet pack advancing, sheet feeding and/or sheet gathering or collating mechanism, and more particularly to a machine for assembling greeting card assortment units.

An object of the present invention is to provide a machine especially adapted for assembling or collating greeting cards into assortment mixtures at maximum speed and with minimum damage to the greeting cards.

A further object of the present invention is to provide a machine providing suction engagement with one side of a sheet for lifting it off a pack, gathering a plurality of these sheets together, and ejecting them from the machine with the opposite sides facing upwardly for proper display or orientation.

A further object of the present invention is to provide a machine for gathering folded sheets and having means to prevent interleaving of the folded sheets during the gathering process.

A further object of the present invention is to provide a sheet handling machine with a pack advancing mechanism having a slow and fast advance and adjustability for flexibility of operation.

A further object of the present invention is to provide means to compensate for variations in thickness across the face of an end sheet of a pack to be fed by a suction-type feeder.

A further object of the present invention is to provide a sheet gathering or collating machine having a valve for sequentially starting or stopping the suction to the sheet feeders in a plurality of packs on said machine so that each gathered sheet unit will be complete and have the same number of sheets therein.

A further object of the present invention is to provide a gathering means for receiving sheets at a loading station with one side up and turning the sheets over before they reach the discharge station thereof.

A further object of the present invention is to provide a gathering means, as set forth in the previous paragraph, with means for laterally shifting the sheets into a compact unit as they move from the loading to the discharge stations.

A further object of the present invention is to provide for proper and complete transference of the sheet through the loading station regardless of the speed and/or intermittency of operation of said machine.

A further object of the present invention is to provide a sheet-handling machine characterized by its operating economy and efficiency, its strong and sturdy nature, and its ability to perform a multiplicity of desirable operations simultaneously.

Other features of this invention reside in the arrangement and design of the parts for carrying out their appropriate functions.

Other objects and advantages of this invention will be apparent from the accompanying drawings and description and the essential features will be set forth in the appended claims.

In the drawings,

FIG. 1 is a side elevational view from the work side of the machine;

FIG. 2 is a side elevational view from the drive side of the machine;

FIG. 3 is an enlarged view of the gear layout in FIG. 2

2

for providing driving power to the operating components of the machine;

FIG. 4 is a sectional view taken along the line 4—4 of FIG. 3 of the cams for controlling the suction-type sheet feeders;

FIG. 5 is a side elevational view of one sheet feeding unit and of the sheet gathering mechanism in operation;

FIG. 6 is a top plan view of one of the four vertically arranged pack advancing units in FIG. 1 with the view turned end for end;

FIG. 7 is a transverse sectional view through the rear roller of the pack advancing conveyor taken along the line 7—7 of FIG. 6;

FIG. 8 is a sectional view taken along the line 8—8 of FIG. 6;

FIG. 9 is sectional view taken along the line 9—9 of FIG. 6 showing the pack advancing ratchet wheel operatively engaged by both the slow and fast advancing pawls;

FIG. 10 is a sectional view taken along the line 10—10 of FIG. 6;

FIG. 11 is a view taken along the line 11—11 of FIG. 6 showing the solenoid-operated mechanism for activating or deactivating the fast pack-advanced pawl;

FIG. 12 is a side elevational view of one of the pack advancing mechanisms looking upwardly from the bottom of FIG. 6;

FIG. 12a is a vertical sectional view taken along line 12a—12a in FIG. 12 of one of the pack side guides;

FIG. 13 is a sectional view taken along the line 13—13 showing the gears and cams for causing pack advance;

FIG. 14 is an enlarged view of the upper right-hand portion of FIG. 12;

FIG. 15 is a vertical sectional view taken along the line 15—15 of FIG. 14 through the mechanism for adjusting the length of stroke of the slow pack advance;

FIG. 16 is a top view taken along the line 16—16 showing the locking means for this stroke adjusting mechanism;

FIG. 17 is an electrical diagram of the control for one of the fast pack advance mechanisms;

FIG. 18 is a transverse sectional view through the control cabinet in FIG. 1 of both the cyclic suction and the sequential starting and stopping valves for controlling the suction applied to the four suction-type sheet feeders in FIG. 1;

FIG. 19 is a side elevational view of the sequential valve member with one-half of its associated housing, located at the left in FIG. 18, for controlling the sequential starting and stopping of the suction feeders;

FIG. 20 is a view taken along the line 20—20 of FIG. 18 looking outwardly from the center of the control cabinet toward the sheet packs and disclosing the cyclic suction valve for controlling the suction to all of the suction feeders and synchronized with their common cycle of movement;

FIG. 21 is a side elevational view taken along the line 21—21 of the sequential valve and the suction line;

FIG. 22 is a view taken along the line 22—22 of FIG. 18 through the reset and control for the sequential valve;

FIG. 23 is a view from along the line 23—23 of FIG. 20;

FIG. 24 is a sectional view taken along the line 24—24 of FIG. 21;

FIG. 25 is a horizontal sectional view taken through the suction manifold, the suction controlling valves and the conduit connecting these valves along the line 25—25 of FIG. 18;

FIG. 26 is a side elevational view, taken in the same direction as FIG. 1, of one of the suction-type sheet feeding heads and of the driving mechanism therefor located within the control cabinet;

FIG. 27 is a sectional view taken along the line 27—27 of FIG. 26;

FIG. 28 is a vertical sectional view taken along the line 28—28 showing the adjustability of the suction elements on a suction-type feeding head;

FIG. 29 is a transverse sectional view through the control cabinet of FIG. 1 looking toward the right thereof from between the suction-type sheet feeders and the sheet gathering mechanism and showing the sheet delivery feeding rolls;

FIG. 30 is a longitudinal sectional view taken along the line 30—30 of FIG. 29;

FIG. 31 is a top plan view of the suction-type sheet feeder, sheet delivery feed rolls, and sheet gathering mechanism;

FIG. 32 is a vertical sectional view taken along the line 32—32 of FIG. 31 showing the side guide structure for the sheet gathering conveyor;

FIG. 33 is a vertical sectional view taken along the line 33—33 of FIG. 31 showing the vertical, endless conveyor of the gathering mechanism with folded greeting cards therein;

FIG. 34 is a transverse, elevational view looking toward the left from the loading side of the gathering conveyor in FIG. 1;

FIG. 34a is a vertical sectional view taken along line 34a—34a of FIG. 34 through the vertical conveyor, with parts omitted for clarity, but including a stop to prevent interleaving on one side and a conveyor protector strip on the other;

FIG. 35 is a horizontal sectional view taken along the line 35—35 of FIG. 34 through the sheet-gathering conveyor;

FIG. 36 is a vertical, longitudinal central view through the sheet unit gathering means and sheet unit ejection means therefrom, taken in the same direction as FIG. 2;

FIG. 37 is a front end view of the machine looking toward the left at the right end of FIGS. 2 and 36;

FIG. 38 is a vertical, sectional view of the ejector arm taken along the line 38—38 of FIG. 37;

FIG. 39 is a view taken along the line 39—39 of FIG. 36 of one of the actuating links of the ejector arm;

FIG. 40 is a sectional view taken along the line 40—40 of FIG. 36 of another actuating link of the ejector arm, while

FIG. 41 is a horizontal sectional view taken along the line 41—41 of FIG. 36.

Before the mechanism here illustrated is specifically described, it is to be understood that the invention here involved is not limited to the structural details or arrangement of parts here shown since sheet and card handling machines embodying the present invention may take various forms. It is also to be understood that the phraseology or terminology herein employed is for purposes of description and not of limitation since the scope of the present invention is denoted by the appended claims.

This collating machine or sheet gathering machine is especially adapted for collating greeting cards into units or groups for greeting card mixture assortments in which each card in the box or assortment is or can be different so that the purchaser may buy in one box or package, for example, four or more greeting cards with each one being different.

Although greeting cards have many variations in construction, they are all capable of being handled by this machine. One of the greeting cards C, shown in FIG. 5 by way of example, is a sheet folded to form overlapping sheet sections C1, C2 with a fold C3 while the other greeting card C' is of single sheet thickness having an edge C3', corresponding to folded edge C3.

However, other greeting cards may be formed with a uniform variation in thickness by a sheet folded into four quarters so that each section is of double thickness. Also, each greeting card may be formed by a plurality of folded

7 sheets stapled together at their folds to form a greeting card with four or more sheet sections instead of the two in the illustrated greeting card C. The sheet may be of thin or thick stock. The sheet section C2 or card C' in FIG. 5 may have variations in thickness across the face (in the direction parallel to and/or perpendicular to the fold C3 or edge C3') caused by (1) variations in its area relative to section C1 by having a die cut design forming its periphery remote from fold C3, or (2) by ornamentation C6 or C6' applied in localized areas to the outer face C4 of section C2 or outer face C4' of card C'. This ornamentation may take the form of ribbons, bows, flocking, chatons (material resembling a precious stone), etc. formed on or secured to the outer face C4 or C4', such as shown at C6 or C6' in FIG. 5. Hence, this display design, ornamentation, or die cut will cause variation in the thickness of each folded sheet so as to cause problems during sheet pack advancing and sheet feeding. However, the words "sheet" or "greeting card" used herein refers to a single sheet, a sheet folded into overlapping sheet sections of single or multiple thickness, a plurality of folded sheets stapled or otherwise secured together, or a sheet or plurality of connected sheets with or without ornamentation, die cutting or thickness variations since some greeting cards come without these complications and many features of the machine are applicable to ordinary sheets.

This machine has a plurality of sheet advancing and feeding components A of any suitable number, here shown as four in number and vertically arranged in FIG. 30. Each has a horizontally extending feed board B adapted to advance a pack of greeting cards resting thereon by their folds C3 or edges C3', such as shown by pack P in FIG. 5, from the right end toward the left end of the machine in FIG. 1 to a sheet feeder F. All greeting cards in one pack P are similar but cards in different packs are different to provide variety in the mixture. These different greeting cards may vary in thickness, ornamentation, and other features to make their handling more difficult but to provide a variety of greeting cards in each unit gathered by this machine. Each pack P in FIG. 5 is preferably loaded on the right end with the greeting cards angling upwardly toward the left for ease of loading the machine. As the pack is advanced toward left toward the feeder F, the greeting cards are turned over so as to incline upwardly toward the right and to be in proper position for feed-off. The greeting card has its smooth outer back face C5 or C5' facing upwardly for engagement by the suction-type sheet feeder S in FIG. 5 to provide positive suction engagement on its smooth surface, to prevent harming the flocking or other ornamentation C6, and to gently lift it off the pack P. The suction pick-up position is kept generally uniform even though there may exist variations in the thickness of the card both perpendicular to and/or parallel to the fold C3 or edge C3' (FIGS. 5 and 28) and variations in the overall card thickness between the four different packs P. All four suction-type feeders in FIG. 1 move together to pick the end card off the feed-off end of the packs P and feed them fold-first into the four vertically arranged feed rolls R. If they were fed fold last (open side first), it would be difficult to feed them through rolls R without damage. These crease the card folds C3 more firmly and feed them into the appropriate sheet unit supporting means U in FIG. 5 of the vertically traveling conveyor of gathering means G in such a manner as to prevent interleaving. The upwardly moving run of gathering means G has four cards in each supporting means U after it travels upwardly past the upper set of feed rolls R in FIG. 1. The gathering means G pulls the cards laterally (both perpendicular and parallel to the fold C3 or edge C3') into a compact unit as they move across the top of the gathering means G in FIG. 1. A card unit ejector or discharger E in FIGS. 1 and 36 ejects individually each unit of four cards by pushing

outwardly against the folds C3 or edges C3' to eject them from the gathering means G onto any waiting receiving mechanism with the card ornamentation C6 or C6' facing upwardly for proper display so that if the cards are immediately inserted into boxes, they will be properly oriented. Hence, gathering means G has turned the cards over between pack feed-off and ejection. It should be noted that the cards C always have the folded edge C3 presented where likelihood of damage is the greatest and to permit easy handling: the cards C rest upon this fold on feed board B; are fed fold first by sheet feeder F; and are stopped, supported, pulled together into a compact unit, and ejected by pressure on the fold in the gathering means G. There is no danger to the thin edges of the greeting card C remote from the fold. All cards, when ejected, will be in a compact unit; none will be interleaved; and all designs will face upwardly and in the same direction when the purchaser thumbs through the box or other display support so as to make an attractive display.

For clarity, many parts have been omitted in the different views, but at least some of the rigidly interconnected frame members, each having a reference numeral prefix "F," are shown throughout. The machine frame F includes a vertical post F1 in FIGS. 1 and 6 supported at the bottom by a suitable base to support the rear of feed boards B, each including parallel side bars F6 and F7 in FIGS. 1, 2 and 6 joined together by front and rear spacers F4 and F5 in FIG. 6. The framework of the control cabinet is formed by a side plate F8 in FIG. 1 comprising a vertical leg F8a secured to one end of a flat plate F8b and a vertical post F8b' secured to the other end of the plate in a generally common vertical plane with a vertical post F11 on the drive side of the feed boards B. The top of leg F8a is secured to the lowest bar F6 while posts F10 (a continuation of plate F8b) and F11 are secured at spaced apart points to bars F6. Posts F14 and F15 in FIG. 2 are secured at their bottoms to spaced apart top ends of plate F16 generally in a common plane parallel to the other plane a spaced distance farther away from bars F6 with spacers secured between these frame members forming these parallel planes to maintain the spacing and parallel relationship. Side plate F8 also includes vertically extending plates F8e (FIG. 1) and F8f (FIG. 34) secured together with plate F8e secured to plate F8d so as to be generally coplanar. Vertically extending plates F8f and F20 in FIG. 34 are maintained generally by cross bars F25, F26 and F27; and are located in front of frame side bars F6 and F7 respectively.

FIGS. 2 and 3 disclose the gear drive for the machine. In FIG. 3, a gear 39, driven by a motor or suitable drive shaft 51, meshes with and drives in sequence gears 40, 41, 42, 43, 44, 45, 46, 47, 48, 49 and 50. Gears 40 and 43 are secured to and carried by shafts 52 and 54 respectively. Gears 41 and 42, 44 and 45, 46 and 47, 48 and 49 are secured to and rotate respectively with shafts 53, 55, 56, and 57. Gear 50 is carried by shaft 58. Shafts 52, 53, 55, 56, 57 and 58 are each rotatably journaled in frame member F16; shaft 54 in frame members F8 and F20; and shafts 53, 55, 56, 57 and 58 in the frame member F8. It has been found that an operative machine results when the gears 39 to 50 inclusive bear the teeth or diameter ratios of four, twelve, twelve, four, twelve, four, three, nine, seven, seven, 9 1/3 and 4 2/3. As will be brought out in more detail hereinafter, shafts 52 and 53 actuate the ejector arm in FIG. 36, shaft 54 actuates not only the sequential starting and stopping valve in FIG. 21 but also the vertical conveyor of the sheet gathering means in FIG. 36, shaft 55 is normally provided with a hand wheel to permit manual turnover of the gear train (FIG. 1), shaft 56 of FIG. 4 provides the cyclic operation of the suction valves in FIG. 20 and the sucker head movement in FIG. 26, and shafts 57 and 58 provide respectively slow and fast advance for the

sheet packs in FIG. 12. Hence, shafts 52, 53, 56 and 57 rotate at the same speed; shaft 58 rotates at twice this speed; and shaft 54 rotates at 1/3 this speed. Therefore, the card unit ejector E in FIG. 36, the cyclic suction valve in FIG. 20, the suction type sheet feeders S in FIG. 26, and the slow pack advance pawl on the left in FIG. 9 have the same operation cycle frequency. The vertically traveling conveyor G in FIG. 36 is designed so that it is moved vertically by shaft 54 the distance between two adjacent sheet unit supporting means U in FIG. 5 during an operation cycle. The sequential valve in FIG. 21 is advanced once each third cycle by shaft 54 since there are three supporting means U between adjacent vertically spaced apart feed boards B in FIGS. 1 and 5. The sequential valve, the cyclic suction valve, the suction feeder movement, and the pack advance is performed simultaneously for all four feed boards B in FIG. 1.

Back advancing and sheet positioning for sheet feed-off

For each feed board B, means is provided for advancing the pack P toward the pick-up position for engagement by suction-type sheet feeder S, as shown in FIG. 5. This pack advancer construction is shown in more detail in FIGS. 5 to 17. Feed board B includes a frame plate member F2 secured to side bars F6 and F7 and having a smooth flat top surface extending along the length of the machine with rollers 66, 67 at opposite ends rotatably supported between frame members F6, F7 with a plurality of laterally spaced apart endless bands 68, extending over the rollers and frame member F2 while being kept spaced apart to prevent lateral walking by a plurality of posts F30 projecting down from frame plate F2 in FIG. 7, adapted to be driven thereby so as to provide a conveying means for advancing toward the left in FIG. 5 the sheets of the pack presented thereto in an on-edge position.

The end of the feed board B is formed by L-shaped member 72 secured to side bars F6, F7 and having vertically extending end wall 72a to arrest pack advance, a horizontally extending bottom wall 72b ahead of bands 68, and rearwardly extending fingers 72c in FIGS. 5, 6 and 30 spacing apart the bands 68. Fingers 72c and wall 72b are suitably beveled on the left side in FIG. 30 to raise the cards thereon during pack advance.

Pack guide side walls 59 and 60 in FIG. 6 are adjustably mounted on the frame to accommodate a wide variety of card sizes. Wall 59 in FIG. 6 is generally L-shape in transverse section with the horizontal flange having a downwardly projecting pin at its right end in FIG. 6, selectively insertable in any one of the holes 72d of bottom wall 72b and having an elongated slot 59a at its left end slidably receiving a nut and bolt clamp unit 61 at the distal end of an arm 62 pivoted to frame member F7 at 62a. Wall 60 in FIGS. 6, 12 and 12a has protruding away from the pack horizontally therefrom two racks 61 secured thereto spaced along the length thereof in FIG. 12. At each frame member F6 is secured a post 63 with a horizontally extending rack guide 63a formed thereon. Shaft 64 is rotatably supported in both posts 63; has pinion gears 71, 71 pinned to opposite ends; and has a knurled adjustment knob secured intermediate the ends. One post 63 has two levers 72, 72' pivotally secured thereto at 72a and having respectively lock teeth 72b, 72b' spaced apart one-half the pitch of gear 71 so that spring 73, secured at opposite ends to post 63 and extending over the levers to urge them downwardly, can lock the adjustment of side wall 60 by one-half tooth steps.

Ratchet wheel 70 (one for each feed board B) in FIGS. 6, 9 and 14 is secured to the common shaft 69 supporting roller 66 in FIGS. 5 and 6 for rotation about the shaft axis for advancing the pack on the frame by means in FIG. 9 of two pawls, a first pawl 74 and a second pawl 75, for driving the ratchet wheel and providing respectively slow and fast pack advance with each pawl being independently operable with the ratchet wheel 70. The

drive for these pawls is shown most clearly in FIGS. 12 and 14 wherein both pawls receive a common drive by shafts 57, 58 interconnected by gears 49, 50 in the gear train of FIG. 3. Each pawl is driven by its associated shaft through an independent linkage means for continuously reciprocating it independently of the operation of the other pawl. These pawls are driven respectively by cams 80s, 80f in FIG. 12 driving follower links 81s, 81f; links 82s, 82f (serving as common links for driving the eight pawls for the four feed boards B) mounted for reciprocation in guide blocks F31, F32 secured respectively to frame members F8, F15; links 83s, 83f; and arms 84s, 84f pivotally mounted on shaft 69. Each link is pivotally connected at opposite ends to its associated driving member. The pawls 74, 75 of FIGS. 9 and 12 are pivotally connected to the respective arms 84s, 84f and are normally biased by a spring or gravity into operative engagement with ratchet wheel 70.

The drive of the pawls is constructed so that fast advance pawl 75 is oscillated through a greater effective advancing stroke per unit of time than the slow advance pawl 74. Since gears 49 and 50 in FIG. 3 bear the diametrical ratios of 2:1, shaft 58 rotates at twice the speed of shaft 57 and pawl 75 and makes two pack advancing strokes per one made by slow advance pawl 74. Also, the effective stroke length of pawl 75 will be greater than that of pawl 74 when the parts are in the FIG. 12 or FIG. 14 position since the link 83f applies its actuating movement at a shorter radial length on arm 84f from the axis of rotation of shaft 69.

Means is provided for adjusting the length of advancing stroke by the slow advance pawl 74. In FIG. 14, pawl arm 84s has a T-slot 84s' adapted to slidably receive a block with a pivot 86 for pivotally connecting together arm 84s, link 83s and connecting link 83 while permitting movement of this pivot radially toward and away from the axis of rotation of shaft 69: adjustment of this radial length will change the arcuate length of advancing stroke of pawl 74. An adjustment knob 89 in FIGS. 1, 5 and 15 is rotatably mounted in frame bar members F6, F7 and fixed against movement along the frame so that rotation of the knob 69 will move pivot 86 along slot 84s'. Knob 89 has a shaft 90 extending under the pack P with a pinion 91 secured to the opposite end for driving lengthwise a rack 92 secured by a bracket 93 to the left end of link 83 in FIG. 14. The bracket has an elongated slot 93a slidably mounted over the outer end of shaft 90 to permit this relative movement while a collar 95, secured to shaft 90, prevents disengagement between shaft 90 and slot 93a.

Locking means is provided in FIGS. 1 and 16 for selectively locking the pinion and adjustment knob 89 against rotation so that a preselected pack advancing action will be continuously performed by pawl 74. A lever 97 in FIGS. 1 and 16 is pivotally connected to frame bar member F7 by pivot pin 93 and is adapted to have its nose 97a detachably engaged with any one of four suitably spaced notches in the periphery of disk portion 89a of knob 89. A spring loaded plunger bears against the side of the lever 97 to frictionally retain it in the locked position of FIG. 16 by a ball and detent action, or the lever 97 may be spring biased toward its lock position in FIG. 16.

When the thickness of pack P under the suction type feeder is too small in FIG. 5 so as to indicate that additional pack advance is required, fast advance pawl 75 in FIG. 9 then operatively engages the ratchet 70 to provide the additional advance. A mask 100 in FIG. 9 is swingable between two extreme positions, by oscillation about the central axis of shaft 69, for rendering pawl 75 fully operative or inoperative with respect to the ratchet wheel 70. The position illustrated in FIG. 9 is the inoperative position while the operative position is assumed when the mask 100 is swung counterclockwise therefrom. The mask 100 is mounted on a carrier bar 101 extending

parallel to shaft 69, upon which a clamp cover 102 is secured by two straddling screws 103 to secure the mask thereto. An additional screw 103 in FIGS. 6 and 11 secures the outer end of the carrier bar 101 to a rotatable disk 104, rotatably mounted for oscillation about the axis of shaft 69.

A separate electrical solenoid operated means in FIGS. 6 and 11 is provided for each pack to swing this mask 100 between these positions for activating or deactivating the fast advance by permitting or preventing this pawl 75 from having driving engagement with ratchet wheel 70. Here, a solenoid 105 is secured to frame bar member F12 connected to frame post F11. One end of downwardly extending bar F12 in FIG. 11 has pivotally connected thereto one end of a link 107 having a slot 107a at the opposite end slidably over a pin 109 carried by the disk 104. A return tension-type spring 108 biases the mask 100 to the fast advance inoperative position shown in FIG. 9 by biasing the mask to move in a clockwise direction in FIG. 9 with mask 100 under the fast advance pawl 75. When the solenoid 105 is energized, its solenoid armature 105a is pulled toward the left from the FIG. 11 position so that tension-type, pull spring 111, connected at opposite ends to armature 105a and bar 101, oscillates mask 100 in the counterclockwise direction against the bias of tension spring 108 so as to move the mask 100 out of blocking engagement with pawl 75 so that fast advance can be performed by this pawl. Slot 107a is of sufficient length to permit this range of movement of pin 109 therein.

The electrical control circuit for this operation is shown in FIG. 17 with a separate control circuit of the type illustrated for each feed board B. Suction type feeder head S in FIG. 5 carries therewith an electrical contact 121 in FIGS. 17 and 26 that is located between contacts 122, 123 carried by the frame for respectively opening or closing the solenoid energizing circuit. As will be brought out in further detail hereinafter, the vertical location of contact 121 at this time will be determined by the thickness of the pack P in FIG. 5 at the feed-off end thereof. Power is supplied to the control circuit from power lines L1, L2 through a step-down transformer 120 to the control voltage while the full power of lines L1, L2 is used to energize the solenoid 105.

The operation of the electrical control circuit in FIG. 17 is most readily understood by assuming that the fast advance pawl 75 is inoperative, the solenoid 105 is de-energized and the height of pack P at the feed-off end in FIG. 5 is being lowered by the continuous feed of sheets therefrom so that the contact 121 in FIG. 17 is located between contacts 122 and 123 but is rapidly approaching contact 123. Then, relay 126 is normally closed and relay 127 is normally open so that the contacts thereof assume the position shown in FIG. 17. The solenoid 105 is de-energized since relay contact 127-1 is open. When contact 121 hits contact 123 on the frame to indicate that the pack P is at a dangerously low level at the feed-off end thereof, the circuit is formed from transformer 120 through relay coil 127, contact 123, contact 121, and the common grounds back to the transformer 120. This circuit energizes relay coil 127 to close relay contacts 127-1 and 127-2. Closing of relay contact 127-1 energizes solenoid 105 so as to swing mask 100 counterclockwise in FIG. 9 out of blocking engagement with respect to pawl 75; then, pawl 75 can perform the fast pack advance function. A holding circuit is also formed to keep relay 127 energized after the contacts 121, 123 separate as the height of pack P builds up at the feed-off position. This holding circuit is from transformer 120 through closed relay contact 126-1, closed relay contact 127-2, relay coil 127, and back to the transformer 120. Solenoid 105 remains energized to provide the fast advance until contacts 121 and 122 engage. When the upper limit of height of pack P at the feed-off position has been reached, fast ad-

vance is no longer required. This forms a circuit from transformer 120 through relay coil 126, contact 122, contact 121, and back to the transformer 120 through the common grounds. Energizing of relay coil 126 opens relay contact 126-1 to break the previously described holding circuit to de-energize solenoid 187 as relay coil 127 is de-energized and relay contact 127-1 is opened.

Both contacts 122 and 123 have definite stops but are spring loaded permitting movement away from these stops so as to take up overtravel of contact 121. Contact 123 has a stem 123a telescoped in frame member F34 in FIG. 17, secured to frame post member F10, biased upwardly by compression spring 124 with upward movement limited by lock nuts 123b screwed onto the bottom of stem 123a. Upper contact 122 is pivoted to frame member F11 at 122a with its distal end biased downwardly against frame stop member F35, secured to frame post member F10, by a tension spring 125 secured at opposite ends to contact 122 and the frame.

This pack advance mechanism has great flexibility in use since greeting cards vary greatly in thickness from a single thin sheet without ornamentation to a plurality of folded sheets having protruding ornamentation from one face. The slow advance mechanism for each feed board B is preferably independent of all of the others on the machine and usable over the entire range. The adjustability of the slow advance by turning adjustment knob 89 provides rough adjustment for single sheets of thin stock, a card formed from a plurality of folded sheets, thick or thin ornamentation, etc. This adjustment by knob 89 also reduces frequency of operation of solenoid 185. Generally, knobs 89 are each set so that the slow, constant advance is just slightly slower than is required by the card thickness in their associated card packs. The fast advance by pawl 75 in FIG. 9 allows for the difference between the required advance and the actual advance by pawl 74; allows for the different packed tightnesses in the different groups of cards on each feed board; keeps the feed-off end of each pack properly formed; and allows for substantial gaps in the pack P, especially between groups of sheets loaded at different times but combining together to form the complete pack P. As brought out before, pawl 75 is movable with a greater frequency and through a greater advancing stroke length than the other pawl 74 to normally provide a faster advance; however, the phase relationship between driving cams 80s, 80f in FIG. 12 may also be set so that the pawl strokes are additive, either completely or partially. Hence, the fast advance is the summation of the effective strokes of both pawls, which is greater than only the effective stroke of pawl 75. However, even when mask 100 is located between pawl 75 and ratchet wheel 70 in FIG. 9 so as to inactivate the fast advance pawl stroke, the slow advance pawl 74 is operable continuously to provide a slow advance at all times.

Although it is necessary in FIG. 5 to have the cards picked up by suction-type sheet feeder S, with the sheets inclined upwardly and away from the feeder S, it is desirable to load additional sheets into the pack onto the feed board B on the right end of the machine in FIGS. 1 and 5 with the sheets inclined in the opposite direction, toward the feeder S, so that the additional sheets need only be placed upon the top of the right end of the pack P instead of tucked thereunder. When this method of loading is used, means is required for reversing the inclination of the sheets as they are advanced along the feed board B by their lower edges C3 or C3' contacting the conveying bands 68. Here, a roller member 130 in FIG. 5, rotatably mounted on bracket 129 in FIG. 6 secured to guide wall 60, extends across the path of travel of the upward edges of the sheets in the pack P so as to engage the sheets of the pack opposite the conveying bands 68. Since this roller member 130 is fixed to the frame against movement along the direction of advance of the conveying band 68, it will reverse the in-

clination of the sheets of pack P being fed forwardly in on-edge relationship as they are advanced in the manner shown in FIG. 5. Although the roller member 130 per se will work satisfactorily under some conditions, a band to joggle the sheets down into proper orientation for pick-up by suction feeder S is the preferred construction illustrated in FIG. 5. Although any type extensible band may be used, FIG. 5 illustrates a band comprising flexible, relatively non-extensible band portion 131 connected at one end to a tension spring 132 with the band portion 131 and spring 132 connected at the opposite ends to the suction-type sheet feeder S so that the lower run thereof is movable with the feed stroke. The band portion 131 extends around the roller member 130 and is movable back and forth as the suction feeder S moves toward the left and then returns to the FIG. 5 position.

It has been found desirable to build up a thickness of cards at the feed-off end of the pack to allow for the pack thickness difference between contacts 122 and 123 in FIG. 17 for controlling fast advance, to permit the card being fed from the pack along a fairly flat path into feed roller unit R to clear the top of end wall 72a of the feed board B, and to provide consistent feeding action.

However, difficulties may occur in attempting to obtain generally the same end card feed off position with different card constructions. These difficulties may occur if the end of the pack P in FIG. 5 either advances horizontally along the flat horizontal surface at the end of the feed board, to a feed off position without climbing end wall 72a or advances into the right angle corner and up end wall 72a on the end of the feed board to a feed off position. First, the greeting card ornamentation C6 sometimes includes ribbon bow, chaton, or object projecting a substantial distance outwardly from surface C4 to C4' and located remote from the fold C3 or edge C3' so as to cause an undesirable forward swing or bulge by the top of pack P. These sheets each vary in thickness across their sheet face generally normal to the lower edge C3' of each sheet in FIG. 5. This projection, caused for example by ribbon bow C6' in FIG. 5, will normally interfere with the guiding of the cards or sheets into proper angular orientation for proper pick-up by suction-type feeder S. Here, a beveled edge 135 in FIG. 5 has been provided at the feed-off end of the feed board B so as to fan out the lower edges of the end sheets in the pack P to bring the end sheet to the proper feed-off position. Second, the cards have to slide over and relative to each other to go up the right angle feed board end wall 72a to the feed-off position. Cards with delicate ornamentation may be seriously damaged by this relative sliding movement. Cards having flock, or similar material with a frictional slide retarding tendency, over a maximum area of one outer face thereof have sufficient frictional resistance to refuse to slide relative to each other far enough to climb the vertical wall 72a; then the top of the cards in the pack will either swing upwardly and forwardly out of proper angular orientation for pick-up or be seriously damaged by the feeding action.

Both problems are solvable by bent strips 135 in FIG. 5. Here, one or more arcuately bent strips 135 in FIGS. 5 and 6 (one omitted in FIG. 60 to show finger 72c) extend in the direction of pack advance and are removably secured by a hoof end 135a over the upwardly extending end wall 72a in FIG. 5 so as to prevent longitudinal shift of the strips in the direction of pack advance. The opposite end 135b of each strip has its top surface preferably beveled and rests upon a finger 72c and frame plate F2 of the feed board B between adjacent conveying band 68 so as not to be driven forwardly thereby but to lead the advancing pack up the curve, as shown in FIG. 5. These strips 135, whether separate or integrally connected together to form a uniform curve over the full width of the feed board B, have similar concave

curves bent in their upper surfaces and are made of bendable material so as to permit changing the curve for adjusting the degree of raise of the card edges C3' at the feed-off end of the pack P. Of course, the advance of the pack P carries each card or sheet up the strips 135 to generally the same height for sucker pick-up and similar orientation. This bendable feature permits the strips 135 to be independently adjustable for each pack P and sheet thickness thereof so that the sheet at the feed-off position is similarly oriented independently of the variations in sheet thickness. It should also be noted that the edge C3' of the sheets in FIG. 5 would be at the lower edge of the pack in this method of greeting card handling so that the sheet will smoothly travel from feed board plate member F2 up onto and along bendable strips 135 to the proper height with the lower end of the pack P fanned out sufficiently to allow for the additional thickness C6' at the top of the sheets thereof to permit location of the sheet to be fed in a similarly oriented position regardless of the variations in thickness.

Of course, the machine can be used without strips 135, as shown in FIG. 30, if the sheet thickness is uniform or the variation does not interfere with proper feeding.

Suction-type sheet feeding

Four sheet feeding means F in FIGS. 1 and 5 are provided to feed or to deliver simultaneously sheets individually from their associated packs at spaced intervals to the loading run of the gathering means G along which they are located. Each sheet feeding means F includes a suction-type feeder S adapted to pick the end sheet off its associated pack by suction engagement and deliver it fold first into its feeding roll unit R for delivery to the gathering means G.

Each suction-type feeder S includes in FIGS. 26, 27 and 31 means for moving its suction-type feeder head 137 between sheet pick-up position at the feed-off end of the pack in FIG. 5 and a discharge position with the sheet adapted to be driven by sheet roll unit R with a single sheet being fed individually from the pack P during each stroke of the suction-type feeder S. Generally horizontally extending track 138 in FIGS. 26 and 31 is mounted for generally vertical reciprocation on the machine frame and is adapted to support suction head 137 by a roller 154, rotatably mounted to cross bar 143 on the remainder of this head, with this track determining only the maximum lower position of head 137 but having no restriction against upward movement of the roller 154 off the track 138. Track 138 is reciprocated vertically by a bar 139, mounted for vertical reciprocation to frame post member F10 by a guide block F36 and driven by a cam 140 on shaft 56 in FIGS. 3, 4 and 26 with the bar 139 having a follower roll 141 rotatably mounted thereon and being kept into cam engagement by weight 142 or a suitable spring secured at opposite ends to bar 139 and the frame. Four similar tracks 138 (one at each feed board B) are carried by bar 139.

Means is also provided in FIGS. 26, 27 and 31 for reciprocating head 137 back and forth along the length of the horizontal track 138 between the pick-up and discharge position. This oscillation is caused by a cam 144 carried by shaft 56 in FIGS. 4 and 26 with this cam driving a follower roll 145 rotatably mounted on one arm of oscillatable bell crank 146, pivoted to frame members F3 and F16, so as to move a link 147 pivotally connected to the other arm of the bell crank. The upper end of link 147 in FIG. 26 is pivotally connected to a connecting link 149 pivotally connected to one arm 148a of a bell crank 148 (one bell crank being located at each of the suction-type feeders S and link 149 being the common connecting link therebetween) pivotally connected to depending lug type member F38 on frame member F7. A suitable tension spring 153 in FIG. 31 may be connected at opposite ends to link 149 and the pivotal mounting of bell crank 146 to assure proper operation. Two other parallel arms

148b, 148b in FIG. 31 of this bell crank oscillate about the bell crank pivot to move parallel links 150, 150 pivotally connected at one end to arms 148b and at the other end to cross bar 143 having roller 154 so as to move the suction head 137 back and forth over the horizontal track 138 while keeping this head properly oriented. Bar 143 is rotatably mounted in lower link 150 of FIG. 31 and is secured to the upper one by a clamp screw 152 either to clamp bar 143 in a given angular position to retain orientation of suction head 137 or to adjust the tilt of bar 143 about its longitudinal axis to change the card pickup position and suction head orientation for different card sizes and types for proper feeding action. A tension spring 151 is connected at opposite ends to the pivot of bell crank 148 and to the link 150 so as to resiliently urge roller 154 of suction head 137 down against the horizontal track 138 during this oscillation and reciprocation movement. The phase relationship between and the shape of cams 140, 144 in FIG. 26 are designed, by synchronizing the oscillation 20 of arm 148b and the vertical movement of track 138, to cause the proper sheet-feeding movement to suction head 137 between the sheet pick-up position in FIG. 5 from the discharge end of the pack P to the discharge position with the sheet engaged in the bite of the feeding rolls of 25 unit R.

Each suction-type sheet feeder head 137 includes non-rotatably mounted on octagonal cross bar 143 a bracket 155 in FIGS. 26, 28 and 31 having a rearwardly extending clamp pocket 155a in FIG. 31 of generally U-shape 30 opening rearwardly and non-rotatably held on the octagonal bar 143 by a cover plate 156 pressed against the rearward surface of the bar by a pair of compression springs 153 above and below the bar with each held in position by a screw 157 to frictionally hold bracket 155 35 in place on bar 143 but to permit longitudinal movement of the bracket along the bar. The other end of the bracket has a sleeve 155b in FIGS. 28 and 31 having a generally vertically extending through central bore mounting a carrier 160 in its lower end. The carrier also has 40 a similar frictional locking arrangement with cross bar 167 by means of a U-shape downwardly opening clamp pocket 160a covered by a cover plate 161 biased against the lower end of the bar 167 by a pair of compression springs 163 straddling the bar with each held in position 45 by a screw 162 extending through the cover plate 161 and secured in the carrier 160. The carrier 160 is normally held in its dot-dash line position in FIG. 28 with bar 167 extending horizontally by means of a tension spring 164 connected at one end to a hole in the upper end of the carrier 160 and at the other end to a cross pin 165 extending across the upper end of the bore in sleeve 155b. The transversely extending bar 167, here shown as generally square in cross section, is adapted to 50 support a pair of sucker elements 170, 170 in FIGS. 28 and 31 and connect them for movement together. Each sucker element 170 includes a suction cup 171, preferably formed of resilient material such as rubber, having a downwardly opening mouth for engagement with the end sheet in the pack P; and in FIG. 26 has a rearwardly 55 opening U-shape clamp pocket 170a covered by a cover plate 175 secured in position by two screws 176 straddling bar 167 to provide frictional engagement on this bar against unwanted longitudinal movement along the bar. Suction conduits 177, 177 in FIG. 31 lead from each 60 sucker element 170 to a suction source and are controlled by suitable valves in the manner to be described in more detail hereinafter.

Referring to FIG. 28 it becomes necessary at times when the cards or sheets are particularly cohesive to use 65 suction elements 171, whose lower faces are not parallel to straddling bar 167 but which when in contact with the back C5' of the top card or sheet just prior to engagement of the same and with straddling bar 167 approximately parallel to the aforementioned card surface C5', that 70 form an acute angle with the plane of the surface being 75

contacted and opening toward the outside of the pack, as shown by the lines Z, Z in FIG. 28. Under such circumstances when suction is applied to the back C5' of the card or sheet, it will tend to peel the outer edges of the top sheet off the pack and thereby minimize the tendency to pick up the next card in the pack at the same time.

The frictional engagement provided by cover plates 156, 161 and 175 in FIGS. 26, 28 and 31 permit quick and easy adjustment in the spacing between the suction elements 170 in FIG. 31 and the relation of each with respect to the position at which it engages the card to be fed. Hence, if the card ornamentation, such as C6' in FIG. 5, provides a localized variation in the rear surface of the card or sheet to be fed so as to prevent satisfactory suction engagement, one or both suction elements may be moved laterally out of alignment with this obstruction sufficiently far to permit satisfactory suction engagement by both suction cups 171. Normally the suction elements are spaced as far apart as possible to lift the top card at the lateral edges so as to minimize the tendency to pick up the next card in the pack at the same time.

If the thickness of the ornamentation C6' in FIG. 5 varies in the transverse, horizontal dimension of the sheet in pack P (in a direction parallel to fold C3 or edge C3'), the end sheet at the feed-off position in FIG. 5 may have the edges extending perpendicular to the fold C3 or edge C3' located so that one is considerably higher than the other, as in FIG. 28, because the thickness caused by the orientation C6' under one side has elevated this edge. Then, rigidly mounted sucker elements, being brought down to the feed-off position in FIGS. 5 or 28, would not both squarely meet the outer surface C5' of the sheet to be fed and erratic feeding might occur. The construction shown in FIG. 28 eliminates this difficulty by permitting the transverse bar 167 and the sucker elements 170 thereon to tilt or rock about an axis through carrier 160 extending generally in the direction of feeding movement to allow for the transverse inclination of the card surface C5' in the feed-off position. This provides a lost motion or loose connection between sleeve 155b and bar 167. The illustrated construction is the preferred construction since both suction cups 171 have their downwardly extending mouths oriented similarly to card surface C5' during pack engagement since bar 167 will assume generally the same inclination as this sheet surface, as shown in the solid line position in FIG. 28. However, some of the advantages might be obtainable having only one sucker element 170 mounted for relative movement with respect to the other under these conditions. Also, the resilient spring 164 normally maintains the bar 167 in a normal horizontal position, shown in dot-dash lines, when the sheet ornamentation does not cause the transverse tilt of the sheet surface. However, even after the bar 167 has tilted to the solid line position in FIG. 28, the spring 164 will return it to the normal, horizontal position to properly align horizontally the card edge C3' in FIG. 5 for proper bite by the feed rolls of unit R, in a manner to be described more in detail hereinafter.

A suction source or other suitable suction applying means may be used for individually applying a suction to each of the suction heads 137, if so desired. However, a single suction source is used for all of the heads on the present machine with conduit means operatively connecting each suction head 137 to this suction source. The conduit means is shown in more detail in FIGS. 18, 21, 25 and 31. It includes a conduit 185 leading from a suction source, an elbow 186, a manifold 187 secured to frame member F14, a sequential valve 190 (to be described more in detail later but assumed in the immediately following description to be continuously open), an individual shut-off valve 191 to be shut off to provide individual shut-off for an inactive feed board B when less than four packs P are being gathered, conduit 192, a cyclic suction control slide valve 193 for cutting off

and applying suction to suction cups 171 during each feeding stroke, two fittings 194 and two conduits 177 leading to the suction cups 171. Illustrated valves 190 and 193 are of the flow cut-off type to cut off vacuum but may, instead, be of the closeable vent type wherein the conduits are vented to atmosphere to cut off the vacuum at suction cups 171 or the vent is closed to make the vacuum effective.

Four units of valve 193 are provided in FIG. 20, one 10 for each suction-type feeder S. FIGS. 18, 20 and 25 of the drawings show this valve in more detail for applying the suction to suction cups 171 at the pick-up station in FIG. 5 on pack P and for releasing the suction 15 at the discharge station with the sheet introduced between the bite of the feed rolls of unit R. Each unit of valve 193 includes housing portions 195, 196 secured together by screws 198 each having a compression spring 199 biasing the housing portions together in straddling relationship on the valve member 197; four straddling stop 20 screws 200 are threaded into housing portion 196 to bear against portion 195 (similar to screws 328 in FIG. 25) and locked by a suitable locknut to control the pressure of portions 195, 196 on slide 197. Housing portion 195 is secured to frame member F11 in FIGS. 18 25 and 25. The slide valve member 197 is a one-piece member extending vertically in FIG. 20 to form the slide member for each of the four units of valve 193. At each unit of valve 193, the valve member 197 has a transversely extending slot 197a, as shown in the cut- 30 away portion of FIG. 20, to cut off or permit fluid communication between conduits 192 and 177 for all suction feeders S simultaneously, depending upon the vertical position of the reciprocable valve member 197. This provides a simple construction, economical to manufacture, easy to repair, and low in friction contact since the valve housing portions 195, 196 are provided in pairs, one pair for each of the suction feeders S while valve member 197 is used in common by all. Relief grooves 196a, 196a may be added to portion 196 in FIG. 25 to 40 further reduce friction and to prevent binding of slide 197 therein.

Valve member 197 is reciprocated vertically in timed 45 relationship to the feeding motion of suction head 137 in FIG. 26 (caused by cams 140, 144) so as to simultaneously activate or deactivate the suction at these heads at the appropriate time in the feeding cycle. A cam 202 in FIGS. 4, 20 and 23 is carried by the same shaft 56 as the cams 140, 144 in FIG. 26 for causing the feeding movement so that each cam goes through a complete 50 cycle of operation in each rotation of shaft 56. A bell crank 203, pivotally mounted to frame members F8 and F16, has a follower roller 204 rotatably mounted at the end of one arm and urged into engagement with the periphery of cam 202 by a spring 205 connected at its 55 upper end to the other arm of bell crank 203 and at its lower end to the frame. A link 206 is pivotally connected at opposite ends to the last mentioned arm of the bell crank 203 and to the valve member 197 to cause the proper reciprocation thereof.

A sheet separator 210 is secured, if necessary to be used, to the horizontal wall of pack side guide wall 59 in FIG. 6 to prevent the feeding of more than one sheet from the pack. This separator 210 is of thin, vertical height, is L-shaped in top view, and clamped to this side guide by a clamp plate 211 and a pair of straddling screws 212. A flexible nose 210a of the separator extends out into the path of travel of the sheets of the pack P of FIG. 5 so as to prevent pick-up by suction feeder S of more than one sheet from packing P by engaging the second sheet and preventing cohesion between the sheets.

As previously mentioned, the fast pack advance by pawl 75 in FIG. 9 is controlled by the vertical position of contact 121 in FIG. 17 carried by suction type feeder 75 S in FIGS. 5 and 26. Pack thickness feeler means is

carried by this suction feeder S and is responsive to the condition of the feed-off end of the pack P in FIG. 5 for determining the vertical position of contact 121. Contact 121 in FIGS. 17, 26 and 31 is non-rotatably carried by the crossbar 143. The pack feeler includes a support arm 222 in FIGS. 5 and 31 secured to crossbar 143 by a U-shape bracket 222a and a clamp screw 223 to permit choice of position along the bar length in FIG. 31 for best machine operation. Feeler arm 224 is adjustably secured to the distal end of support arm 222 by a clamp plate 226 secured thereto by thumb screw type clamp screws 227, two in number. A feeler roll 225 is rotatably secured to the lower end of feeler arm 224 and is adapted to make a feeling contact with the feed-off end of pack P in FIG. 5. Cam 140 in FIG. 26 is designed so that track 138 will always be lowered free of roller 154 in the sheet pick-up position; hence, only the thickness or height of the pack P at the feed-off end will determine the vertical location of suction head 137 since track 138 is free to be pulled downwardly away from roller 154. Therefore, the vertical location of head 137 and contact 121 in FIGS. 17 and 26 determines the fast pack advance actuation. When the pack is low so that contacts 121 and 123 engage in FIG. 17, solenoid 105 in FIG. 11 is energized to pull mask 100 counter-clockwise in FIG. 9 to permit operative engagement between fast advance pawl 75 and ratchet wheel 70. When the pack P is at its upper limit of thickness at the feed-off end, contacts 121 and 122 engage to deenergize solenoid 105, and to deactivate fast advance pawl 75 in FIG. 9 by mask 100.

The spring 151 in FIG. 26 serves a dual function. It normally retains the roller 154 down into firm contact with the horizontal track 138 while permitting vertical movement of the head 137 relative to this track at the pick-up position in response to the pack engagement by feeler roll 225 for actuating the control circuit in FIG. 17. Second, the resiliency of spring 151 and gravity causes feeler roll 225 to firmly press against the end of the pack P for properly orienting the end sheet thereof to permit the suction cups 171, 171 to meet this sheet squarely for proper suction engagement therewith.

Sheet feeding by feed rolls

The suction-type sheet feeder S in FIG. 5, at its sheet discharge position, operatively engages the sheet edge C3' into the bite of the roll-type feeder unit R in its pick-up position for power feeding of the single sheet to a discharge position and into the gathering means G. There is a roll-type feeder unit R for each of the four packs and these are vertically arranged beside the loading run of the gathering means G. Each feed roll unit R includes a pair of feed rolls, an upper one and a lower one, having respectively feed roll portions 230 and 232 in FIGS. 5, 29 and 31 with these roll portions mounted respectively to rotate with shafts 231 and 233, the latter being rotatably mounted in frame members F10, F15 and F40 secured to bar F7. The lower feed roll is power driven, preferably by a motor 235 in FIG. 2, separate from the motor used to drive shaft 51 in FIG. 2 for providing input power to the collating machine. This separate motor 235 will always feed the sheets into the gathering means G at the same speed for uniformity of gathering even though it may be desirable to change the speed of shaft 51 to adjust the sheet feeding speed. Motor 235, mounted on a base plate 235a in FIG. 1 pivotally connected at its left end to frame members F8 and F14, in FIG. 2 drives by belt 236 and suitable pulleys the drive gears 237 secured respectively to the power driven roll shafts 233 with intermediate gears 238 rotatably secured to frame post F15 providing the drive between adjacent drive gears 237, one for each of the four roll-type feeder units R in FIG. 2.

Since ornamentation C6' in FIG. 5 may exist on some cards or sheets and may take the form of ribbon bows,

flocking, spangles, etc., it is desirable that this ornamentation not be harmed as it goes through the feeding roll unit R. At least one, if not all, of the feed roll portions 230, 232 is only frictionally engaged with its associated driving shaft so as to be laterally adjustable therewith to move out of driving alignment with the ornamentation C6'. Preferably, the lower feed roll portions 232 are adjustable in this manner. The right end of shaft 231 in FIG. 29 is rotatably mounted in a bearing block 239 adapted to have vertical movement in an elongated vertical slot of frame member F40 while being biased downwardly by a tension spring 240 connected at its lower end to frame member F40 so that the ornamentation C6' will not be harmed during the feeding operation but the feed rolls will be urged into frictional driving contact regardless of the thickness of the card or sheet. The left end of shaft 231 in FIG. 29 may have either a similar spring biased construction or a pivotal connection about a transverse axis with the frame.

Of course, the vertical movement of shaft 231, permitted by spring 240, could be used to actuate a detector for double card feeding or card missing. If the movement of shaft 231 is used to activate a sheet miss or double sheet detecting means, both feed roll portions 230, 232 may be moved out of alignment with the ornamentation so that erroneous detections do not occur.

The feed roll unit R assists in the gathering operation by gathering means G. It should be noted in FIG. 5 that when sheets with a fold C3 are fed, the feed rolls 30 receive the sheet fold first, crease the fold C3 more firmly, keep the sheet folded in flat form during feeding from right to left in FIG. 5, keep the folded sheet properly oriented in a generally horizontal plane, and shoot the folded sheet into the gathering unit so as to prevent 35 interleaving with previously gathered folded sheets in this gathering means G.

Sheet unit gathering

A sheet unit gathering, inverting and transferring means 40 G is provided in FIG. 1 for mechanically gathering or collating sheets C and C' in predetermined units (if all four packs are feeding sheets, the units is of four sheets but some of the advantages are obtained if only one pack is feeding sheets; hence, a unit may have one or 45 more sheets therein) at spaced intervals on the right-hand side thereof in FIG. 1 and to eject each unit individually on the left-hand side thereof in FIG. 1 with the ornamentation thereon properly oriented for packaging or display purposes. Gathering means G is shown in more 50 detail in FIGS. 5, 31, 32, 33, 34, 34a, 35, 36 and 37. It includes a vertically traveling endless conveyor 245 movable past the four vertically arranged sheet feeding units F to receive sheets fed by the feed roll units R to form sheet units. This conveyor includes an endless link 55 chain type conveyor member 246 having an upwardly traveling loading run 246a and a downwardly traveling discharge run 246b having loading and discharge stations respectively therewith the conveyor movable up over the top in moving from loading to discharge. A 60 driving sprocket 247 is driven by shaft 54 of the gear train in FIG. 3 while a driven sprocket 248, rotatably mounted in and between frame members F8f and F20, supports the upper end of this link chain type conveyor member 246 during the driving thereof. A litter cover strip 249 in FIG. 34a (omitted in the other drawing views for clarity) is secured to base 249a adapted to be 65 adjustably moved along an inverted T-way formed by guide base 250 and way caps 250a detachably secured to base 250. Guide base 250 is secured to frame member block F41 in turn secured to frame member plate F42 secured at opposite ends to frame members F8f and F20. It extends upwardly along the conveyor discharge run 246b and over the top of the conveyor between the 70 sheet units and the link chain type conveyor member 246. 75 When the sheets or cards go over the top with vertical

orientation, as in the present disclosure, this becomes rather important because the paper particles adhering to the previously cut cards, flock, loose ornamentation, etc., are shaken downwardly upon and fall on the link chain type econveyor member 246 to cause abnormal wear if litter cover strip 249 is not provided.

The conveyor has a plurality of sheet unit supporting means or pockets U, here 24 in number, spaced along the length of conveyor member 246 with each adapted to receive sheets extending generally transverse to the direction of travel of conveyor member 246. Each sheet unit supporting means U includes a base 252 in FIGS. 31 and 33 secured to endless conveyor member 246 by a pair of brackets 253. An arm connector 254, as well as base 252, is secured to each bracket by screws 258. A pair of arms 255, 256, spaced longitudinally along the endless conveyor member 246, are secured to opposite ends of each arm connector 254 by bolts 257. Each unit supporting means U has four such arms 255, 256 and a pair of arm connectors 254, as shown most clearly in FIG. 37. These form longitudinally spaced apart arm units with each unit having a pair of transversely spaced apart arms, as shown at 255, 255 or 256, 256 in FIG. 37. Also, litter cover strip 249 in FIG. 34a extends between these transversely spaced apart arms 255, 256, as shown by its upward projection in FIG. 34a, so as not to interfere with operation of conveyor 245. The cards or sheets C or C' making up each unit are located between arms 255 and 256, as shown in FIGS. 5 and 33. To guide the travel of each unit supporting means U, each base 252 has projections in FIG. 31 at opposite ends guided by guide members 260, 261 and 262 in FIG. 32 with these bases 252 traveling between guide members 260, 261 and around the outer surfaces of guide members 262. Each of these guide members is secured to frame member F8f or F20.

Means is provided to prevent interleaving between a previously gathered folded sheet and any sheet (single thickness or folded) fed into the gatherer in the manner shown in FIG. 5, and to minimize damage to the ornamentation C6' during the gathering operation. A sheet stop member or arm 264 in FIGS. 5 and 34a extends vertically upwardly between the transversely spaced apart arms 255, 255 and 256, 256 on the loading run 246a to prevent interleaving of the sheet being fed in with the previously gathered, folded sheets forming the unit. By keeping the previously gathered folded sheets fairly close to the outer end of the arms 255, the sheet being fed in has less tendency to interleave than if the previously gathered folded sheet were positioned farther to the left and nearer to endless conveyor member 246 in FIG. 5. This stop member 264 is secured to base 264a adapted to be moved along the inverted T way formed by guide base 250 and detachably secured by way caps 250a. This construction permits adjustment in and out (toward left and right in FIG. 34a) for different size cards being collated by the machine. The stationary stop member 264 does not interfere with operation of the conveyor 245 because it always extends between the transversely spaced apart arms thereof, as shown by its upward projection in FIG. 34. Also, the distal ends of the upper arms 256 are bent upwardly at 256a in FIG. 5 to permit higher speed operation and to prevent the tendency to interleave. Although the machine may be synchronized to feed the card in pocket U at a lower level, the machine is preferably synchronized so that each suction type sheet feeder S and feed roll unit R will feed the sheet from its pack P toward or against the curved portion 256a, as shown in FIG. 5. This construction permits high speed feed of the sheets, prevents interleaving of the folded sheets, and minimizes damage to the ornamentation C6' positioned downwardly during the gathering by minimizing the sliding contact between the ornamentation of the sheet being fed into the unit and the previously gathered sheets of the unit. This

is especially important with thicker cards, which tend to interleave more readily since they provide more bulk in pocket U and have more springiness in their fold.

Spring-type card keeper member 266 in FIG. 5 may be used with or alternatively instead of any of the structure for preventing interleaving mentioned in the previous paragraph. Member 266 is a single continuous strip of spring steel bent in the manner shown and having its ends held to frame member F4 by plate 267 secured thereto by screws. Three members 266 are provided, one between each adjacent pair of feed boards. As conveyor 245 moves upwardly, inclined portion 266a urges any outwardly protruding cards back against stop member 264, portion 266a may frictionally urge the top card section or face C1 of a folded card down into tightly folded position to prevent interleaving with the card being fed in, and the card fed in will be held in compact vertical relation with the others in the unit and prevented from bouncing to the right out of pocket U after it hits stop member 264. The upper and lower ends of member 266 are bent to the right to prevent rolls 232 and 230 respectively from pulling any outwardly protruding card from any pocket U moving therewith; this would damage the card, short out the unit, and cause a jam. One or more of these advantages may be obtained depending on the distance between frame member F4 and portion 266a as determined by the location of member 266 secured by clamp plate 267.

Gathering means G includes a pair of side guides 268, 269 in FIGS. 1, 31, 34 and 35 mounted on frame members F20 and F8f, each of generally inverted U-shape in side view in FIG. 1, and manufactured from generally uniform thick material with this material being preferably clear plastic to permit visual observation of the gathering and transferring operation. The side guides extend longitudinally along and straddle the sheet units and supporting arms 255, 256 with generally parallel sheet guide faces 268b, 269b. These guides 268, 269 are supported by horizontally extending parallel bars 272, 273 (four in number) secured to front and rear support bars 274, 275 by bolts 276 with these bars in turn secured to the side guides in the manner illustrated.

The feeding action of roll-type feed units R tend to bring the sheets making up the units into closer registration. The side guides are provided with tapered mouth openings surfaces 268a, 269a in FIG. 35 extending along the full length of the loading run of the conveyor and immediately in front of the roll feed units R with these mouths opening outwardly to pull the fed sheets laterally into alignment to form a more compact unit during the feeding operation.

The sheets forming each unit are moved laterally together in both directions by the gathering means as the units travel from the loading to the discharge station. As the sheet units travel from the loading to the discharge station, they will be shifted transversely of the conveyor travel into a still tighter unit by the flat sheet guide faces 268b, 269b of the side guides. Although these faces are flat, they taper in the direction of conveyor travel because support bars 275 in FIG. 35 are shorter than the support bars 274 while horizontal bars 272, 273 are parallel to each other. Hence, as the conveyor member 246 travels from the loading station, over the top, and to the discharge station, the flat sheet guide faces 268b, 269b will pull the sheets laterally (transverse to the direction of conveyor travel) into a more compact unit. Also, as the sheet units go over the top, gravity will pull them down between the arms 255, 256 and against the arm connectors 254 as a locating stop (see FIG. 33) so as to shift the sheets of the unit laterally (in the direction toward and away from the conveyor member 246) into a more compact unit in this direction also. Litter cover strip 249 in FIG. 34a does not interfere with this action since it is located between the two arm connectors 254 of each unit U, as shown by an upward projection there-

of in FIG. 34 and by the location of the outer surfaces thereof at the top of FIG. 34a.

When different size cards are being collated, it is desirable to adjust the width between the guide faces 268b, 269b by moving both side guides 268, 269 simultaneously toward or away from each other during set-up of the machine. A rotatably mounted adjustment knob 278 in FIGS. 1 and 34 will turn by a shaft (journaled in frame member F20) the bevel gears 279 for rotating shaft 281, rotatably mounted in frame members F26 and F27 in FIGS. 34 and 35, to drive simultaneously two coaxially spaced apart pinion gear 282 for simultaneously moving racks 284, 284 reciprocably guided on frame members F26 and F27 and secured at their outer ends to the respective horizontal bars 272, 273 secured in turn for moving side guides 268, 269 inwardly or outwardly as desired.

Hence, faces 268b, 269b will always be equidistant from arms 255, 256 so that each sheet unit will be approximately centrally supported during conveyance with no tendency to tilt off the arms; the arms do not have to be adjusted laterally during set-up. However, pack sidewalls 59, 60 in FIG. 6 may have to be adjusted laterally so that the sheets are properly fed to the gathering means G.

Sheet unit ejection

Means is provided in FIGS. 36-41 inclusive for discharging together all the sheets of a unit from the gathering and inverting means conveyor 245. This means includes in FIGS. 36 to 41 inclusive an ejector arm 290, and means for moving it in timed relationship to the conveyor 245 and between the transversely spaced apart conveyor arms 255, 255 and 256, 256 in FIG. 37 toward and away from the endless conveyor member 246 in FIG. 36 to eject individually each sheet unit by pushing outwardly against the sheet edge C3 or C3' to eject the units from between arms 255, 256 and guide faces 268b, 269b. Arm connectors 254 are of sufficient thickness that both the distal end of ejector arm 290 in FIG. 36 and the litter cover strip 249 in FIG. 34a will fit behind the card units on the discharge conveyor run 246b.

The ejector arm 290 is movable vertically up and down by cam 291 (in FIG. 36 but omitted in FIG. 37 for clarity) secured to shaft 52 of the gear train in FIG. 3 and is movable horizontally back and forth by an oscillating movement by cam 292 in FIG. 36 secured to gear train shaft 53 so as to move synchronously with the endless conveyor member 246.

The vertical movement is caused in FIG. 36 by a link 295, pivotally connected at its left end in FIG. 36 to frame member F8f, having a cam roll follower 296 at its right end biased into peripheral engagement with cam 291 by tension spring 297 secured at its upper end to link 295 and at its lower end to frame member F8f. Connecting link 298 is pivotally connected at its upper end to link 296 and at its lower end to a cross shaft 302 having ejector arm 290 clamped thereto in FIG. 38 and movable vertically by the relative movement permitted by parallel links 301, 301 in FIG. 41, each pivotally secured at one end to shaft 302 and secured at the other end to a cross shaft 299 pivotally secured to frame members F8f and F20. Hence, as cam 291 rotates, follower 296, cross shaft 302 and ejector arm 290 will raise and lower.

Ejector arm 290 is also simultaneously moved back and forth toward and away from conveyor member 246 by oscillating its supporting cross shaft 302 by the mechanism in FIG. 36. A link 304 has a cam roll follower 303 rotatably secured to one end while the other end of the link is telescoped within a sleeve 305 with a spring 307 kept in compression by lock nuts 306, as illustrated in FIG. 36. Link 311 is pivotally secured at opposite ends to frame member F8f and link 304 while link 309 is non-rotatably secured to cross shaft 302 at its lower end and is pivotally connected by a pivot and clamp bolt 314 to sleeve 305 at a point spaced from shaft 302. A tension spring 312 is secured at one end to frame member F8 and at the other to link 311 to resiliently urge roll follower

303 constantly into peripheral contact with cam 292. Pivot and clamp bolt 314 is movable along the length of slot 309a in the upper end of link 309 and may be secured at any point therealong for adjustment of the arcuate angle of oscillation of shaft 302 and the length of back and forth travel of the upper or distal end of ejector arm 290.

In FIGS. 36 and 37, sleeve 305 and compression spring 307 are used with link 304 to provide a link variable instead of fixed in length for several reasons. First, if the sheets of a unit are jammed against an obstruction of a sheet unit receiving machine, etc. located to the right in FIG. 36 of the distal ends of arms 255, 256 while ejector arm 290 is attempting to push them to the right between these arms, machine part bending or breakage will not occur since spring 307 will permit arm 290 to remain stationary while cam 292 continues to push follower 303 toward the right in FIG. 36. Second, since link 309 and 311 are not parallel and not of equal length, the length of one of the links must necessarily change as the angular relation between them changes during the oscillation of shaft 302. Third, oscillation of shaft 302 about shaft 299 will change the center to center distances between shaft 302 and the pivot at the lower end of link 311 as shaft 302 is moved vertically by cam 291. Fourth, adjustment in the length of stroke may be obtained by moving bolt 314 along the slot 309a to change the effective length of link 309; however, the end points of any given length stroke may be altered by unclamping arm 290 in FIGS. 37, 38 and 41 from shaft 302 and reclamping it thereon in a new angular position. Hence, spring 307 may change in overall length during jamming and during each cycle of movement of the ejector arm 290.

Sequential starting and stopping of sheet feeding

Sequential valve 190 is provided in FIGS. 18, 19, 21, 22, 23 and 24 for changing sequentially the suction exerted on the four suction-type sheet feeders S in FIG. 1 by the suction source in timed relationship to the travel of the gathering conveyor 245 so that the suction applied to these feeders is initiated sequentially from the bottom to the top in FIG. 1, remains active during continuous running of the machine, and is stopped sequentially in the same manner so that all units on the gathering conveyor 245 have an equal number of sheets therein. Although the collating machine in FIG. 1 will operate satisfactorily with out the sequential valve 190, the use of the valve is preferred so that the operator will be assured that each unit has the same number of sheets.

A frame structure in FIGS. 22 and 25 supports the components of this sequential valve 190. Frame post member F14 has secured thereto the manifold 187 in FIG. 25, and frame members F111, F112, F113, F114, and F115 in FIG. 22 secured together and to frame member F14 by screws F117, F118, F119 and F120.

A one-piece valve slide member 325 in FIGS. 18, 19, 21, 22 and 25 extends across the suction conduits to suction type feeders S in FIG. 1 so as to be movable between shut and open positions for each conduit for respectively cutting off or permitting flow into the individual flow conduits. This valve member 325 is vertically reciprocatable between valve housing portions 326, 327 in FIG. 25 with these portions biased into controlled sealing relationship with valve member 325 by screws 324, each surrounded by a compression spring 324a, and by stop screws 328 and a lock nut 328a in FIGS. 21 and 25 to serve the same purpose as stop screws 209 and the lock nuts thereon in FIG. 20. Valve housing portion 326 is secured to the manifold 187 by screws 329 while the manifold in turn is secured to the frame member F14.

This valve member 325 is moved in stepwise fashion endwise in one direction by a pawl and ratchet type actuating device. Cam 330 in FIG. 21 is secured to shaft 54 in the gear train of FIG. 3 so as to move the valve member 325 in step fashion in one direction by engaging the follower 332 on the distal ends of a link 331 pivotally

secured at its upper end to one of the frame members to reciprocate a link 334 pivoted at opposite ends, to oscillate a bell crank 335 pivotally secured to frame member F14, and to reciprocate a link 336 in FIGS. 18 and 21 having a pawl 337. The upper end of link 336 is guided in frame member F115, which is normally biased toward the right in FIG. 18 or upwardly in FIG. 22 by a spring 352 located in recess F115a in frame member F115 so as to urge pawl 337 into driving engagement with the teeth of ratchet rack 347.

Shaft 54 is adapted to make one complete rotation while three sheet unit supporting means U pass a given point since the gears 42 and 43 in FIG. 3 bear the tooth number ratio of 1 and 3. Since there are two means U between each adjacent pair of rolls R in FIG. 5 when a means U is aligned with each, pawl 337 reciprocates through a complete cycle as any given means U advances from one roll unit R to the one immediately above it.

This ratchet rack 347 is secured to valve member 325 so as to cause movement thereof. A horizontal connecting bar 340 in FIGS. 18, 21 and 22 is secured to the top of valve member 325 by a screw 341 and is secured to the top of a rack support 343 by a screw 342. Two screws 345 secure a gear rack 344 to this rack support 343 while the screw 346 secures the ratchet rack 347 to this same rack support 343.

A manual actuating device is also provided for moving the valve member 325. Here, a knob 349 in FIGS. 1, 18 and 22 is provided on the work side of the machine in FIG. 1 for rotating a shaft 348, rotatably supported at its right end in the outer shell of the drive mechanism housing and at its left end in FIG. 18 by bearing F112a in frame member F112, so as to rotate a pinion 350 in operative engagement with rack 344.

Valve member 325 is constructed so that this sequential activation and sequential deactivation of the suction to the suction-type feeders S will occur. In FIG. 19, valve housing portion 327 has a plurality of equally spaced apart apertures 327a, 327b, 327c, and 327d aligned with corresponding apertures in valve housing portion 326, as shown in FIG. 18, with these apertures corresponding respectively to the four suction-type feeders S in FIG. 1 vertically arranged on the machine. Valve member 325 has a plurality of elongated apertures 325a, 325b, 325c, and 325d corresponding respective to these apertures. When valve member 325 is in the FIG. 19 position, suction is shut off to all of the suction type feeders S since the valve member is in its shut position for cutting off flow in the individual suction conduits. Pawl 337 in FIG. 18 is then at the top of ratchet rack 347. After pawl 337 is lowered by cam 330 in FIG. 21, it feeds ratchet rack tooth 347a upwardly as pawl 337 advances upwardly to its highest position. Then, ratchet rack 347 and valve member 325 have been elevated sufficiently so that the upper end of the slot 325a in FIG. 19 has exposed the aperture 327a, so that the valve member is in the open position with respect to the lower suction-type feeder S in FIG. 1 and a sheet may be fed thereby. As the gathering conveyor 245 moves upwardly and the sheet containing pocket U formed by arms 255, 256 in FIG. 5 approaches the next higher vertically arranged suction feeder S, pawl 337 in FIG. 18 has advanced ratchet rack tooth 347b so that slot 325b in FIG. 19 has exposed aperture 327b and suction has been applied to the suction feeder S (second from the bottom in vertical height in FIG. 1) so that the first sheet fed from this second pack will be fed into the same pocket in the manner shown in FIG. 5. This operation continues until slot 325d has exposed aperture 327d in FIG. 19 and pawl 337 in FIG. 18 has fed ratchet rack tooth 347d upwardly so that all the suction feeders S in FIG. 1 have suction. Hence, the suction has been applied to the four suction feeders S in FIG. 1 sequentially. The suction will remain active during continuous running of the machine because flat 347e on the ratchet rack in FIG. 18 does not permit the pawl 337 to reach the next ratchet rack tooth 347a.

The suction may be also stopped or deactivated sequentially so that all the units will have an equal number of sheets. Then, knob 349 in FIG. 18 is turned until an indicator thereon aligns with an indicator on the outer cabinet wall so that pinion 350 will elevate the rack 344 until pawl 337 can engage ratchet tooth 347a' in FIG. 18. After pawl 337 has moved this tooth upwardly to the end of its stroke, the bottom of slot 325a in FIG. 19 will have traveled upwardly past aperture 327a so that the lowest suction type feeder S will be deactivated since the suction will be cut off thereto. The pawl 337 will continue to feed the ratchet rack 347 upwardly until it has reached its highest position after engaging and raising the lowest rack tooth; then, each of the slots in FIG. 19 will be moved above their corresponding apertures to cut off the suction to all of the suction-type feeders S to inactivate the sheet feeding even though the gear train in FIG. 3 continues to drive the machine.

In FIG. 19, the slots 325a-325d are equal in number 20 to the apertures 327a-327d and the suction-type feeder heads S in FIG. 1. Also, corresponding ends (for example the upper ends) of the slots 325a-325d in FIG. 19 are spaced closer together than the associated corresponding apertures 327a-327d so as to permit the sequential starting and stopping operation. The elongated slot ends serve as valve opening and closing portions.

After the collating machine has stopped, it may be desirable to again start up the machine by sequential initiation of suction. Then, it is necessary to return the 30 ratchet rack 347 and valve member 325 downwardly to its initial position shown in FIG. 19. To do this, it is necessary to overcome the bias of spring 352 in FIG. 22 so as to disengage the pawl 337 from the teeth of the ratchet rack 347 to permit return movement by rotating 35 knob 349 to drive the rack 344 downwardly by the pinion 350 in FIG. 18. Pawl 337 is disengaged by pushing actuating knob 356 on rod 355 in FIG. 18 toward the left and overcoming the bias of the compression spring 357 telescoped thereover and located between a shoulder 355b 40 on shaft 355 and frame member F114. This spring 357 normally biases the shoulder 355a carried by the rod into engagement with the drive mechanism housing, supporting the right end of rod 355, to keep the rod, in the position shown in FIG. 18, out of pawl disengaging relationship. As the rod 355 is pushed toward the left, it protrudes farther through the hole F114a in frame member F114 in FIG. 22 so as to push against one face of plate 359 secured at its left ends by screws 360 in FIG. 18 to pawl carrying link 336 in FIGS. 18 and 22 so as to overcome the bias of spring 352. Then knob 349 may 45 be rotated so that the racks 344, 347 and valve member 325 will be carried downwardly to their lowest position.

It should be noted that knob 349, pinion 350 and rack 344 serve as a single manually operated means for sequentially starting and stopping suction application to 50 the feeder heads S and for returning the valve member 325 in the opposite direction to its original position.

Many of the actuating links and other members in the drawings have a plurality of parallel holes along the length thereof to permit adjustment of stroke. It should 60 also be clearly evident that similar holes can be provided in many of the other members for the same purpose whenever necessary to obtain satisfactory operation of the machine.

Various changes in details and arrangement of parts 65 can be made by one skilled in the art without departing from either the spirit of this invention or the scope of the appended claims.

What is claimed is:

1. In a machine, a sheet unit gathering and inverting means comprising a vertically traveling endless conveyor having opposite vertically traveling up and down runs for providing loading and discharge stations respectively with the units movable over the top in moving from loading to discharge, means for feeding sheets individual-

ly from a pack onto said sheet gathering and inverting conveyor including a suction type sheet feeder for suction engaging the outer one face of the end sheet, lifting its opposite other face off the next adjoining sheet of an associated pack, and feeding the sheet individually toward the loading run of the gathering conveyor, and means for discharging said sheet from said gathering and inverting conveyor with said other face of the sheet facing generally upwardly for display orientation.

2. In a machine for collating sheets having a display design on one outer face and having a smooth outer other face, a sheet unit gathering and inverting means comprising a vertically traveling endless conveyor having opposite vertically traveling runs for providing loading and discharge stations, said conveyor having a plurality of sheet unit supporting means spaced therealong for receiving sheets extending generally transverse to the direction of conveyor travel, means for feeding sheets individually from a plurality of packs onto said sheet gathering and inverting conveyor including a plurality of suction type sheet feeders spaced along the loading run, means for moving each suction type sheet feeder in timed relationship with the conveyor and for suction engaging the outer smooth other face of an end sheet, lifting its opposite one face off the next adjoining sheet of an associated pack, and feeding the sheet individually toward the loading run of the gathering and inverting conveyor to form sheet units, and means for discharging all sheets of a unit together from said gathering and inverting conveyor with said other faces of the sheets facing generally upwardly for display orientation.

3. In a machine for collating sheets folded into overlapping sheet sections having a display design on one outer face and having a smooth outer other face, a sheet unit gathering and inverting means comprising a vertically traveling endless conveyor having opposite vertically traveling runs for providing loading and discharge, said conveyor having a plurality of sheet unit supporting means spaced therealong for receiving sheets, a plurality of suction type sheet feeders and power driven feed roll assemblies spaced along the loading run, means for moving each suction type sheet feeder in timed relationship with the conveyor and for suction engaging the outer smooth back other face of an end sheet, lifting its opposite one face off the next adjoining sheet of an associated pack, and feeding the sheet individually fold first into its associated feed rolls to be fed thereby onto said supporting means onto the loading run of the conveyor to form sheet units, and means for discharging all sheets of a unit together from said gathering and inverting conveyor by pushing outwardly against the sheet folds of the unit individually with said one face of the sheets facing generally upwardly for display orientation.

4. In a machine for collating sheets folded into overlapping sheet sections having ornamentation on one outer face and having a smooth outer other face, a frame, a sheet unit gathering and inverting means comprising a vertically traveling endless conveyor having opposite generally parallel vertically traveling up and down runs for providing loading and discharge, said conveyor having a plurality of sheet unit supporting means spaced therealong for receiving sheets, a plurality of suction type sheet feeders and power driven feed roll assemblies spaced along the loading run, means for moving each suction type sheet feeder in timed relationship with the conveyor for suction engaging the outer smooth back other face of an end sheet, lifting its opposite one face off the next adjoining sheet of an associated pack, and feeding the sheet individually fold first into its associated feed rolls, said associated feed rolls being actuatable to feed said sheet into one of said sheet unit supporting means on said conveyor to form part of a sheet unit, means locating each of said unit supporting means in sheet receiving position with at least two of said sheet feeders for receiving at least one sheet from each of the latter, means for pre-

venting interleaving of the folded sheets of the units, and means for discharging all sheets of a unit together from said gathering and inverting conveyor by pushing outwardly against the sheet folds of the unit individually with said one face of the sheets facing generally upwardly for display orientation.

5. In a machine for feeding and gathering sheets, a frame, a sheet unit gathering conveyor, said conveyor including an endless member movable in the direction of conveyor travel, said conveyor having a plurality of sheet unit supporting means spaced along and carried by said conveyor member for receiving sheets extending generally transverse to the direction of conveyor travel with each sheet unit supporting means including a pair of arms spaced longitudinally apart along and secured to said endless member, a sheet feeder for feeding sheets individually onto said supporting means, a pair of side guides on said frame extending longitudinally along the conveyor member and having generally parallel sheet guide faces straddling the arms and sheets, and means for moving said guide faces toward or away from each other to accommodate different size sheets.

6. In a collating machine, a frame, plurality of vertically arranged feed pack supports on said frame, a sheet gathering conveyor movable vertically past the feed-off end of said packs, said conveyor including a conveyor member having a plurality of sheet unit supporting means spaced along and carried thereby for receiving sheets extending generally transverse to the direction of conveyor travel with each supporting means including a narrow arm secured to said conveyor member, sheet feeders on said frame for feeding sheets individually onto said arm, a pair of side guides on said frame extending longitudinally along the conveyor member and having generally parallel sheet guide faces straddling the arms and sheets, and means for moving said guide faces toward or away from each other to accommodate different size sheets while maintaining them equidistant from said arms so that the sheet units will be centrally supported thereby, said feed pack supports including independently adjustable pack side wall guides.

7. In a collating machine, a frame, a plurality of vertically arranged feed pack supports on said frame, a sheet gathering conveyor movable vertically past the feed-off end of said packs, said conveyor including a conveyor member having a plurality of sheet unit supporting means spaced along and carried thereby for receiving sheets extending generally transverse to the direction of conveyor travel with each supporting means including a pair of arms spaced transversely apart and secured to said conveyor member, sheet feeders on said frame for feeding sheets individually onto said pair of arms, a pair of side guides on said frame extending longitudinally along the conveyor member and having generally parallel sheet guide faces straddling the arms and sheets, means for moving said guide faces toward or away from each other to accommodate different size sheets while maintaining them equidistant from the outer edges of said arms so that the sheet units will be centrally supported thereby, said feed pack supports including independently adjustable pack side wall guides, and an arm on said frame extending in the direction of conveyor travel between said pair of arms for exerting pressure centrally on the sheet unit edges.

8. In a machine for collating sheets, a sheet unit gathering means comprising a vertically traveling conveyor having opposite vertically traveling up and down runs between loading and discharge stations with the units movable over the top in moving from loading to discharge, said conveyor having a plurality of sheet unit supporting means spaced therealong for receiving sheets extending generally transverse to the direction of conveyor travel, a plurality of sheet feeders for feeding sheets individually onto said supporting means of the conveyor to form sheet units, and a pair of guides extending longitudinally along

the conveyor and having guide faces straddling the units and tapering toward each other over the top in the direction of travel of said units for pulling sheets laterally into a compact unit while gravity pulls them laterally together in the other direction.

9. In a machine for gathering sheets, a frame, a sheet unit gathering vertically traveling conveyor having an endless conveyor member forming opposite vertically traveling runs for providing loading and discharge stations respectively, said conveyor having a plurality of sheet unit supporting means spaced along and carried by said conveyor member for receiving sheets extending generally transverse to the direction of conveyor member travel, a plurality of sheet feeders for feeding sheets individually onto said supporting means to form sheet units, each sheet unit supporting means including a pair of arms spaced longitudinally apart along and secured to said endless member, and a pair of side guides on said frame extending longitudinally along the conveyor member and having generally parallel guide faces straddling the arms and sheets but with said faces spaced closer on the discharge run than the loading run and tapering toward each other in the direction of travel of said units for pulling sheets laterally into compact units.

10. In a machine for gathering sheets, a frame, a sheet unit gathering vertically traveling conveyor having conveyor members forming opposite generally vertically traveling runs between loading and discharge with the units movable over the top in moving from loading to discharge, said conveyor having a plurality of sheet unit supporting means spaced along and carried by said conveyor member for receiving sheets extending generally transverse to the direction of conveyor member travel, each sheet unit supporting means including a pair of arms spaced longitudinally apart along and secured to said endless member, a litter cover strip secured to said frame located at the top of said conveyor between the sheet units and endless member, and a pair of side guides on said frame extending longitudinally along the conveyor member and having sheet guide faces straddling the arms.

11. In a machine for gathering sheets, a frame, a sheet unit gathering vertically traveling conveyor, said conveyor having a plurality of sheet unit supporting means spaced along and carried thereby for receiving sheets extending generally transverse to the direction of conveyor travel, a plurality of sheet feeders spaced along the loading run, and a pair of side guides extending longitudinally along the conveyor and having generally parallel guide faces straddling the supporting means, said guide faces having a tapered mouth opening outwardly along the loading run to pull the sheets laterally into alignment to form a more compact unit during feeding.

12. In a machine for gathering folded and other sheets, a frame, a sheet gathering conveyor, said conveyor including a member movable in the direction of conveyor travel, said conveyor having a plurality of sheet unit supporting means spaced along and carried by said conveyor member for receiving sheets extending generally transverse to the direction of conveyor travel with each sheet unit supporting means including a pair of arms spaced transversely apart and secured to said member, a sheet feeder, means for moving said sheet feeder in timed relationship with the conveyor member, and a stop member adjustably secured to said frame and extending in the direction of conveyor member travel between said arms to prevent interleaving of a sheet being fed with previously gathered folded sheets of the unit.

13. In a machine for gathering sheets, a frame, a sheet gathering vertically traveling conveyor movable on said frame, said conveyor including a conveyor member movable in the direction of conveyor travel and having a plurality of sheet unit supporting means spaced along and carried by said conveyor member for loosely receiving sheets extending generally transverse to the direction of conveyor travel, a plurality of sheet feeders spaced

along said conveyor to feed sheets from said frame to said sheet unit supporting means with each including a pair of power driven rolls, and a member carried by the frame interposed between said supporting means and said rolls to prevent sheet pull-out from said supporting means by said rolls.

14. In a machine for gathering folded and other sheets, a frame, a sheet gathering vertically traveling conveyor movable on said frame, said conveyor including a conveyor member movable in the direction of conveyor travel and having a plurality of sheet unit supporting means spaced along and carried by said conveyor member for receiving sheets extending generally transverse to the direction of conveyor travel, a plurality of sheet feeders spaced along said conveyor to feed sheets from said frame to said sheet unit supporting means, and a member carried by the frame to fold down the top folded sheet in said supporting means as it approaches the next vertical sheet feeder to prevent interleaving.

15. In a machine for gathering folded and other sheets, a frame, a sheet gathering vertically traveling conveyor movable on said frame, said conveyor including a conveyor member movable in the direction of conveyor travel and having a plurality of sheet unit supporting means spaced along and carried by said conveyor member for loosely receiving sheets extending generally transverse to the direction of conveyor travel, each sheet unit supporting means including a pair of arms spaced transversely apart and secured to said member, a plurality of sheet feeders spaced along said conveyor to feed sheets from said frame to said sheet unit supporting means with each including a pair of power driven rolls, a stop member on said frame extending in the direction of conveyor member travel between said arms to prevent interleaving of the folded sheets of the units, and a member carried by the frame and located between said arms to fold down the top folded sheet in said supporting means as it approaches the next vertical sheet feeder to prevent interleaving and to urge the sheet units against said stop member and away from the rolls to prevent sheet pull-out from said supporting means by said rolls.

16. In a machine for gathering folded sheets, a frame, a feed board on said frame, means for advancing folded sheets along said feed board in fold-on-edge relationship, power driven feed rolls on said frame, means on said frame for feeding the end pack sheet fold first into the bite of said rolls, a sheet gathering conveyor movable along said frame and having a plurality of sheet unit supporting means spaced along and carried thereby, a sheet fold engageable stop means secured to said frame for limiting sheet feed in travel by said feed rolls into the aligned sheet unit supporting means, and a sheet unit ejector engageable with the fold and movable relative to said frame and conveyor for ejecting the sheet unit, whereby the sheet fold receives the operating forces to minimize sheet damage.

17. In a collating machine, a frame, a sheet unit gathering conveyor, said conveyor including an endless member movable in the direction of travel, said conveyor having a plurality of sheet unit supporting means spaced along and carried by said conveyor member for receiving sheets extending generally transverse to the direction of conveyor member travel, a plurality of sheet feeders spaced along the conveyor for feeding sheets individually onto said supporting means of the conveyor to form sheet units, each sheet unit supporting means including a pair of arms spaced transversely apart and secured to said endless member, a stop member adjustably secured to said frame and extending in the direction of conveyor member travel between said arms to prevent interleaving of the folded sheets of the units, and means for discharging all sheets of a unit together from said gathering conveyor, said discharge means including an ejector arm movable in timed relationship to said conveyor member and swingable between the transversely spaced apart arms toward

and away from said conveyor member to eject by pushing against the sheets of the units.

18. In a collating machine for collating folded and other sheets having ornamentation on one outer face and having a smooth outer other face, a frame, a sheet unit gathering and inverting means comprising a conveyor having an endless conveyor member forming opposite generally parallel vertically traveling up and down runs for providing loading and discharge respectively with the units movable over the top in moving from loading to discharge, said conveyor having a plurality of sheet unit supporting means spaced along and carried by said conveyor member for loosely receiving sheets extending generally transverse to the direction of conveyor member travel, a plurality of suction type sheet feeders and power driven feed roll assemblies spaced along the loading run, means for moving said suction type sheet feeder in timed relationship with the conveyor member for suction engaging the outer smooth other faces of end sheets, lifting their opposite one faces off the next adjoining sheets of associated packs, and feeding the sheets individually fold first from a plurality of packs into associated feed rolls to be fed thereby onto said supporting means of the loading run of the gathering and inverting conveyor to form sheet units, each sheet unit supporting means including a pair of arm units spaced longitudinally apart along and secured to said endless member, a litter cover strip secured to said frame located at the top of said conveyor between said sheet units and endless member, each arm unit having a pair of transversely spaced apart arms, a stop member adjustably secured to said frame and extending in the direction of conveyor member travel between said arms to prevent interleaving of a sheet being fed with previously gathered folded sheets of the units by engaging the center of the sheet fed, said gathering and inverting means including a pair of flat side guides on said frame extending longitudinally along the conveyor member and having generally parallel sheet guide faces straddling the arm and sheet units thereof but with said faces spaced closer on the discharge run than the loading run and tapering toward each other in the direction of travel of said units for pulling sheets laterally into a compact unit as they go over the top while gravity pulls them laterally together in the other direction, means for moving said guide faces toward or away from each other to accommodate different size sheets while maintaining them equidistant from the outer edges of said arms so that the sheet units will be centrally supported thereby, said guide faces having a tapered mouth opening outwardly at the loading station to pull the sheets

laterally into alignment to form a more compact unit during feeding, independently adjustable pack side wall guides on said frame, a member carried by the frame and located between said arms to fold down the top folded sheet in said supporting means as it approaches the next vertical sheet feeder to prevent interleaving and to urge the sheet units against said stop member and away from the rolls to prevent sheet pull out from said supporting means by said rolls, and means for discharging all sheets of a unit together from said gathering and inverting means conveyor, said discharge means including an ejector arm movable in timed relationship to said conveyor member and swingable between the transversely spaced apart arms toward and away from said conveyor endless member to eject by pushing outwardly and centrally against the sheet folds of the unit individually from between said arms and guide faces with said one face of the sheets facing generally upwardly for display orientation.

20 19. In a sheet collating machine, a plurality of sheet engageable suction heads each adapted to feed sheets independently from an associated pack, a suction applying means for each suction head, conveyor means movable past said suction heads and adapted to receive sheets fed thereby to form sheet units, means for controlling the suction applying means having a member movable in one direction for changing sequentially the suction exerted on the suction heads in timed relationship to the conveyor means, and means for manually returning said member to its original position including a coacting rack and pinion drive.
